(57) **CLAIM**

The ornamental design for a graduation pendant, as shown and described.

DESCRIPTION

FIG. 1 is a front perspective view of a graduation pendant showing my new design;

FIG. 2 is a front elevational view thereof;

FIG. 3 is back elevational view thereof;

FIG. 4 is a right side elevational view thereof;

FIG. 5 is a left side elevational view thereof;

FIG. 6 is a top view; and,

FIG. 7 is a bottom view.

The broken lines represent portions of the graduation pendant which form no part of the claimed design.
